(57) CLAIM

The ornamental design for a kebab rack, as shown and described.

DESCRIPTION

FIG. 1 is a top plan view of a kebab rack, showing my new design:

FIG. 2 is a bottom plan view thereof;

FIG. 3 is a front elevational view thereof, the rear elevational view being a mirror image thereof;

FIG. 4 is a left side view thereof; and,

FIG. 5 is a right side view thereof.

In the drawings, the broken lines in FIGS. 1-5 depict portions of the design that form no part of the claim.
